UNITED STATES PATENT OFFICE

95,805

DESIGN FOR A MEMORIAL MARKER

Irwin W. Cox, Denver, Colo.

Application November 22, 1933, Serial No. 49,822

Term of patent 14 years

To all whom it may concern:

Be it known that I, Irwin W. Cox, a citizen of the United States, residing at the city and county of Denver, and State of Colorado, have invented a new, original, and ornamental Design for Memorial Marker, of which the following is a specification, reference being had to the accompanying drawing, forming a part of this application.

Fig. 1 is a perspective view of a memorial marker, showing my new design;
Fig. 2 is a top plan view; and
Fig. 3 is an end elevation.

I claim:

The ornamental design for a memorial marker, as shown.

IRWIN W. COX.
